UNITED STATES PATENT OFFICE

2,342,272

BOILER CONSTRUCTION

Bruce Hayter, Santa Fe, N. Mex., assignor to Oil
Devices, Santa Fe, N. Mex., a limited partnership
of Illinois

Application January 21, 1941, Serial No. 375,286

8 Claims. (Cl. 122—156)

My invention relates to an improvement in furnaces and is herein shown in connection with a hot water boiler.

One purpose is the provision of improved efficiency in heat exchange means for such a boiler.

Another purpose is the provision of a boiler which is particularly adapted to pot type burners and in which a circulation of the products of combustion is obtained with maximum efficiency and with a maximum heat exchange.

Another purpose is the provision of a boiler which is well adaptable for use with a booster fan associated with a pot type burner.

Another purpose is the provision of a boiler which is adapted for use with a long radiant flame.

Another purpose is the provision of a boiler which is relatively light and can be handled readily by two men without cranes or jacks.

Another purpose is the provision of improved means for leveling the boiler.

Another purpose is the avoidance of any ceramic fire box and of any substantial heat loss to the floor.

Another purpose is the provision of a boiler which may efficiently be shipped in a complete package, thereby reducing shipping and installation charges.

Another purpose is the provision of a boiler in which no heavy motor is used and electrical consumption is low.

Another purpose is the avoidance of draft losses within the boiler.

Another purpose is the facilitation of cleaning the heat exchange surfaces.

Another purpose is the provision of improved means for permitting observation of the fire.

Other purposes will appear from time to time in the course of the specification and claims.

I illustrate my invention more or less diagrammatically in the accompanying drawings wherein:

Fig. 1 is a plan view with the skeleton parts broken away;

Fig. 2 is a vertical axial section on the line 2—2 of Fig. 1; and

Fig. 3 is a section on the line 3—3 of Fig. 2.

Like parts are indicated by like symbols throughout the specification and drawings.

Referring to the drawings, 1 indicates an outer shell, herein shown as open at the bottom and spaced slightly above the supporting surface. It is provided with a plurality of supporting legs or flanges 2, each of which may carry adjustable floor engaging abutments 3 whereby the fur-

nace can be adjusted or aligned on any suitable supporting surface. I illustrate the shell 1 as cylindrical and with a dome or upwardly convex head 4 located adjacent but below the top of the shell. The top may be closed by a cover plate 5.

6 is an inner cylinder, preferably concentric with the shell 1 and open at the bottom, as at 7. It is partially closed at the top by a closure 8. The dome 4 and the closure 8 may be connected by a passage member 9, preferably concentric with the members 1 and 6. The lower edge of the member 6 may be connected by a wall 10 with the outer shell 1. The space defined by the members 1, 6, 4, 8, 9 and 10 constitutes a water space to which water may be supplied by the intake line 11, and from which hot water may pass along the takeoff line 12.

13 is any suitable temperature gauge connected to the water space, for example by a line 14. Located somewhat below the partition 10 is a horizontal partition 15, centrally apertured to receive the upper edge of the housing 16. 17 is an asbestos rope or other suitable packing located in a flange or shelf 18 adjacent the top of the housing 16. The housing 16 has an inwardly extending flange 19, upon which is suspended the burner pot 20, with top secondary air inlets 21 and a plurality of primary air inlets 22 located at various levels. The pot 20 may be suspended, for example, by means of the short outward flange 23.

24 is any suitable fire ring, centrally apertured as at 25. If desired, a supplemental or upper fire ring 26 may be employed, with a central aperture 27 surrounded by a flange 28. The housing 16 may be held in position for example by a clamp ring 29, and tension members 30 downwardly extending from the partition 15 and having at the bottom wing nuts 31 or any other suitable securing or clamping members.

32 is a partition mounted upon an inner flange 33 of the ring 29. It is centrally apertured as at 34, and through the aperture extends a motor shaft 35 of the motor 36, upon the upper or inner end of which is mounted any suitable booster fan 37. If desired, an abutment plate 38 may be located above the fan to prevent a direct impingement of air upon the bottom of the pot 20. The motor may be supported in any suitable manner, for example upon the plate 39 mounted by members 40 upon the partition 32. Any suitable connections or circuit not herein shown may be employed for connecting the fan with any suitable source of electric power.

41 is any suitable fuel inlet line extending to the bottom of the pot 20 from any suitable source of liquid fuel not herein shown. The walls or partitions 4 and 10 may be connected by a plurality of flues 42 which extend from the space below the partition 10 to the space above the partition 4. The passage of heated gases outwardly through the passage 9 may be adjustably limited by the baffle 43 which has a sleeve 44 screw threaded in relation to a hollow internally screw threaded fitting 45. The fitting 45 has a top cap 46 having a central aperture 47, which may be closed by mica or the like 50, thus permitting inspection of the burner without permitting passage of the heated gases.

In the normal use of the device, fuel admitted to the bottom of the pot 20 is vaporized by the heat of combustion. When the device is burning at full fire, the primary air is provided by the apertures 22, and the mixture thus formed rises upwardly until it receives the secondary air through the passage 21 for complete combustion. The flame then rises up into the center of the space defined by the shell 6. As the member 43 may be adjustably set to allow a relatively small flow of heated gases therethrough to the space above the wall 4, there will be a recirculation of heated gases downwardly along the inner wall of the shell 6, back to the space below the partition 10, and then upwardly through the flues 42 to the space above the partition 4, the heated gases finally escaping along any suitable flue outlet 48.

Any suitable pilot or ignition means not herein shown may be employed.

It will be understood that any suitable door 51 may be employed in the shell 4, as shown in Fig. 3, to give access to the pot, motor, and associated parts. It will also be understood that, if the supply of air about the lower edge of the shell 4 is insufficient, any suitable air inlet means may be employed in the door 51 or elsewhere. In order to have access for cleaning purposes to the flues 42, I illustrate a pair of removable segmental top members or lids 52, which are aligned with the various flues 42. Any suitable control means may be employed for varying the flow of fuel. I illustrate diagrammatically a valve 53. It will be realized that any suitable valve, manual or automatic, may be employed for varying the flow of fuel from the pilot stage or full shutoff to the high fire stage.

It will be realized that, whereas I have described and illustrated a practical and operative device, nevertheless many changes may be made in the size, shape, number and disposition of parts without departing from the spirit of my invention. I therefore wish my description and drawings to be taken as in a broad sense illustrative or diagrammatic, rather than as limiting me to my precise showing.

The use and operation of my invention are as follows:

I illustrate herein a compact unit, inexpensive to manufacture, which may be shipped in a single package. In setting it up the installation man merely unpacks the furnace and sets it on end, with the members 3 engaging the supporting surface. The members 3 being screw threaded in relation to the flanges or legs 2, may be readily set to obtain an accurate vertical alignment of the furnace.

When the fuel valve 53 is set for maximum flow of fuel, the flame will be located generally as shown in Fig. 2. The heated gases impinge

upon the upper wall 8, and an adjustable amount thereof may escape about the baffle 43. Preferably the parts are so adjusted that a substantial proportion of the heated gases of combustion wipe outwardly across the downwardly concave surface of the member 8 and flow down along the vertical inner face of the wall 6 to the space below the wall 10. They then flow about the wall 10 and upwardly through the flues 42, to escape finally above the wall 4 and to flow across the top thereof to the outlet 48. It will thus be evident that the heated gases travel through a path of substantial length, and that they travel prevailingly along vertical heat exchange surfaces.

I preferably maintain a continuous very low pilot, which prevents any danger of ignition failure, explosion, or the like, and provides an extremely safe unit. While the pilot device does not of itself form part of the present invention, I may employ a baffle ring of any suitable form, adjacent, slightly above, or slightly below the lowest row of apertures 22, or I may employ a so-called chimney pilot in connection with the fuel inlet 41.

Preferably but not necessarily I maintain something more than atmospheric pressure by employing the motor 36 to rotate the booster fan 37, which draws air through the aperture 34 and about the plate 38 into the substantially air tight space within the air housing 16. This air is delivered under pressure through the apertures 21 and 22 to support combustion in the pot 20 at low or pilot stage, and at the upper portion or above the pot 20 at the high stage. The inner face of the wall 6 is located to receive the radiant heat of combustion from the pot and flame rising thereabove, in addition to the heat exchange by the direct passage downwardly of the heated gases along the inner face of the wall 6.

I also provide a plurality of air holes 54 in the supporting plate 15, which deliver air to the space below the ring 26. This constitutes an additional supply of secondary air, which increases the capacity of the burner and which may be delivered by natural draft, since it flows from the space between the drum 1 and the air housing 16.

The efficiency of the unit is extremely high, sometimes too high for some installations, but this efficiency can be lowered by opening or increasing the bypass controlled by the baffle or closure 43.

Lighting the burner is easy and may be accomplished by dropping a wooden match or small ball of paper through the top observation hole defined by the fitting 45 and the stem 44 of the baffle 43. The observation hole 47 gives a good view of the operation of the fire at the starting stage or any other time.

While I have illustrated a boiler built as a water boiler, it will be understood that, with little change, it can be converted for use as a steam boiler. It may also be used with any suitable storage tank as a hot water supply heater, or without a storage tank as an instantaneous water heater.

Since the combustion is silent, the boiler in operation under fire is extremely quiet.

It will be understood, of course, that any suitable insulation may be employed. I illustrate for example an insulating jacket 55 applied in any suitable manner to the exterior of the drum 1.

Whereas I have described and shown my boiler as employed in connection with an oil burner, it

will be understood that, because of the ample vertical clearance in the boiler and because of the fact that most of the heating surface is vertical, it may be employed advantageously with other fuels, for example as a stoker boiler.

One of the disadvantages of the present boiler constructions is that adequate vertical distance from the stoker retort to the crown sheet does not exist, with the result that the flame does not have an opportunity to burn itself out and impinges on the crown sheet, with disadvantageous results.

In stoker operation there is a considerable amount of fly ash present. This fly ash collects on the horizontal surfaces, and since it has a considerable insulating effect it quickly cuts down the efficiency of the boiler. As will be apparent from the description and drawings herein, not only are the heat exchange surfaces vertical, but the fly ash will drop back on the fire bed and be purged out in the ash removal operation. Especially in the central combustion chamber, since the gases rise and then reverse themselves, they act in the nature of a fly ash separator.

While the hole 47 makes a good observation window, its primary purpose is for lighting the burner when an oil burner is employed, as a match or piece of paper can be dropped down into the burner pot.

Another advantage of the boiler is that it is adjustable to any chimney condition within reason that is likely to be encountered in the field. Thus, if the chimney is a poor one and therefore needs a high chimney temperature to pull an adequate draft, the bypass 43 can be opened, letting more heat go up the chimney to make it function properly. As a rule, in the field about seventy-five percent of the chimneys employed are usually satisfactory, but I find it highly advantageous to provide a furnace which may be adjusted in order to maintain a sufficiently high stack temperature in such poor chimneys as are encountered in the field.

I claim:

1. In a furnace and burner assembly, an exterior housing, a fluid fuel burner located in a lower portion of said housing, a container for fluid to be heated, located in an upper portion of the housing, said container having an inner wall defining a space vertically aligned with said burner, said container having upper and lower walls extending inwardly from said outer housing, the upper wall at a level below the top of the exterior housing, a wall spaced below said upper wall extending inwardly from an upper portion of said inner wall, said last mentioned wall being connected to the upper wall by a passage member aligned with said burner, a plurality of flues connecting said upper and lower walls and providing communication between the spaces above and below said container, and a flue outlet in communication with the space above said upper wall, said exterior housing having an inspection orifice in line with said passage member.

2. In a furnace and burner assembly, an exterior housing, a fluid fuel burner located in a lower portion of said housing, a container for the fluid to be heated, located in an upper portion of said housing, said container having an inner wall defining a space vertically aligned with said burner, and upper and lower walls extending inwardly from said outer housing, the lower wall at a level above the top of the burner, the upper wall at a level below the top of the exterior housing, a plurality of generally vertical flues connecting said walls and providing communication between

the spaces below and above said container, a flue outlet in communication with the space above the upper wall, and means for causing the heated products of combustion to travel downwardly across the surface of said inner container wall and upwardly through said flues, including a top closure for the space defined by said inner wall, said closure having an aperture vertically aligned with said burner, the top of said exterior housing having an inspection orifice in line with said aperture.

3. In a furnace and burner assembly, an exterior housing, a fluid fuel burner located in a lower portion of said housing, a container for the fluid to be heated, located in an upper portion of said housing, said container having an inner wall defining a space vertically aligned with said burner, and upper and lower walls extending inwardly from said outer housing, the lower wall at a level above the top of the burner, the upper wall at a level below the top of the exterior housing, a plurality of generally vertical flues connecting said walls and providing communication between the spaces below and above said container, a flue outlet in communication with the space above the upper wall, and means for causing the heated products of combustion to travel downwardly across the surface of said inner container wall and upwardly through said flues, including a top closure for the space defined by said inner wall, said closure having an aperture vertically aligned with said burner, the top of said exterior housing having an inspection orifice in line with said aperture, and means effective to close said aperture or, selectively, to vary its cross sectional area of discharge to the space above said upper wall, including a closure plate, said plate having a hollow stem, the hollow of said stem being aligned between said inspection orifice and the burner.

4. In a furnace, an exterior shell and an interior shell defining a container for the fluid to be heated, a bottom member for said container extending between said exterior and interior shells, at a level substantially above the bottom of said exterior shell, a top member for said container, a plurality of generally vertical flue elements extending between said top and bottom members, a top head for said exterior shell located above said top member and defining with it a flue space in communication with said vertical flue elements, said top head being apertured in alignment with said flues, removable cover means for said apertures, and an additional flue vertically aligned with said burner and extending from the space within said interior shell to the space between the top member of the container and the top head of the exterior shell, and a closure therefor, and means for positioning it selectively at a plurality of positions between the closed and the fully open position.

5. In a furnace, an exterior shell and an interior shell defining a container for the fluid to be heated, a bottom member for said container extending between said exterior and interior shells, at a level substantially above the bottom of said exterior shell, a top member for said container, a plurality of generally vertical flue elements extending between said top and bottom members, a top head for said exterior shell located above said top member and defining with it a flue space in communication with said vertical flue elements, and an additional flue vertically aligned with said burner and extending from the space within said interior shell to the

space between the top member of the container and the top head of the exterior shell, and a closure therefor, and means for positioning it selectively at a plurality of positions between the closed and the fully open position.

6. In a furnace and burner assembly for pot type burners burning liquid fuel, an outer circumferential wall, a top closure therefor, a burner pot located in a lower portion of the space enclosed by said wall, means for delivering fuel thereto, a hot water container located within said outer wall at a level entirely above the top of said burner, said container including an inner wall positioned within the outer wall and defining a space vertically aligned with the burner pot, a bottom partition extending from said outer wall to the lower edge of the inner wall, defining an open space located above the top of the burner, a transverse partition forming the top of the container and defining, with the top closure of the outer wall, an open flue space above the top of the container, means for withdrawing flue gases from said flue space, a central flue passage element generally vertically aligned with the burner pot and extending from the top of the space within said container to said open flue space above the container, and a plurality of additional flue passages extending from bottom to top of the container and located between the inner wall of the container and said outer wall, the space within the container being closed at its upper end by a partition wall extending inwardly from the top of the inner wall of the container and spaced downwardly below the container top.

7. In a furnace and burner assembly for pot type burners burning liquid fuel, an outer circumferential wall, a top closure therefor, a burner pot located in a lower portion of the space enclosed by said wall, means for delivering fuel thereto, a hot water container located within said outer wall at a level entirely above the top of said burner, said container including an inner wall positioned within the outer wall and defining a space vertically aligned with the burner pot, a bottom partition extending from said outer wall to the lower edge of the inner wall, defining an open space located above the top of the burner, a transverse partition forming the

top of the container and defining, with the top closure of the outer wall, an open flue space above the top of the container, means for withdrawing flue gases from said flue space, a central flue passage element generally vertically aligned with the burner pot and extending from the top of the space within said container, to said open flue space above the container, means for selectively closing said flue passage or leaving it open, and 10 a plurality of additional flue passages extending from bottom to top of the container and located between the inner wall of the container and said outer wall, the space within the container being closed at its upper end by a partition wall extending inwardly from the top of the inner wall of the container and spaced downwardly below the container top.

8. In a furnace and burner assembly for pot type burners burning liquid fuel, an outer circumferential wall, a top closure therefor, a burner pot located in a lower portion of the space enclosed by said wall, means for delivering fuel thereto, a hot water container located within said outer wall at a level entirely above the top of said burner, said container including an inner wall positioned within the outer wall and defining a space vertically aligned with the burner pot, a bottom partition extending from said outer wall to the lower edge of the inner wall, defining an open space located above the top of the burner, a transverse partition forming the top of the container and defining, with the top of the container, means for withdrawing flue gases from said flue space, a central flue passage element generally vertically aligned with the burner pot and extending from the top of the space within said container to said open flue space above the container, means for varying the opening of said flue passage through a range from 20 fully closed to wide open, and a plurality of additional flue passages extending from bottom to top of the container and located between the inner wall of the container and said outer wall, the space within the container being closed at 25 its upper end by a partition wall extending inwardly from the top of the inner wall of the container and spaced downwardly below the container top.

BRUCE HAYTER.
